UNITED STATES PATENT OFFICE.

LAZARD KAHN, OF HAMILTON, OHIO, ASSIGNOR TO F. & L. KAHN & BROS., OF SAME PLACE.

DESIGN FOR A STOVE-DOOR.

SPECIFICATION forming part of Design No. 23,014, dated January 23, 1894.

Application filed August 2, 1893. Serial No. 482,205. Term of patent 14 years.

To all whom it may concern:

Be it known that I, LAZARD KAHN, of Hamilton, Butler county, Ohio, have invented and produced a new and original Design for Stove-Doors, of which the following is a specification, reference being had to the accompanying drawing, which is a perspective view of a stove-door, illustrating my design.

My design is characterized by having a rectangular, horizontally disposed door panel A, provided with a defining margin D, and having circular boss-shaped closed front registers arranged in horizontal series and projecting outwardly from the face of the panel and provided at the center of their fronts with handles C.

What I claim is—

The design for a stove door, herein shown and described.

LAZARD KAHN.
